PROCESS FOR TREATING HYDROCARBONS

Application filed November 25, 1927. Serial No. 235,502.

This invention relates to the treatment of hydrocarbons. These hydrocarbons may be obtained from any source, such as the distillation of crude petroleum, cracking of heavy hydrocarbons, hydrogenation of coal, distillation or extraction of oil shale, casing head gasoline, etc. Our invention is also applicable to the individual hydrocarbons as well as to mixtures. These untreated products are usually undesirable for use because of the presence of substances, such as certain sulphur compounds and unstable hydrocarbons, which have an unpleasant odor, which resinsify on standing, etc. Thus in gasoline for motor use these undesirables must be reduced to render the product stable and saleable. In the succeeding specification our invention will be particularly described with reference to what is commonly known as gasoline, but we do not wish to be limited thereto since our invention is applicable to the treatment of hydrocarbons in general.

The treating of crude gasoline usually results in the formation of certain solid and liquid by-products which may be polymers of unsaturated compounds in the gasoline or may be compounds of the treating agent with certain constituents of the gasoline, or both. In general, such by-products are troublesome since they tend to foul the treating apparatus and the treating agent. In many cases it is necessary for economic reasons to recover the treating agent from its mixture with the by-products; this, of course, adds an extra operation, and may be attended with considerable difficulty and expense. This prohibits the use of relatively expensive treating agents even though they produce a superior product. Thus, for example, such difficulties form one of the principal reasons why alkali metals have not been used commercially in treating crude gasolines even though it is known that the treated product is of excellent quality.

The object of this invention is to provide a process whereby the excessive fouling or the accumulation of treatment by-products in treating baths or media for hydrocarbons is avoided. A further object is to provide a process whereby alkali metals may be used as treating agents under such conditions that

relatively large quantities of hydrocarbons are treated per unit of alkali metal consumed, with negligible loss of unreacted metal.

We have discovered that excessive fouling of the treating media can be avoided by suspending the treating agent in a liquid of such characteristics that the hydrocarbon to be treated can be added, treated, and removed from the treating medium as vapor, the while supplying fresh suspending liquid, with or without additional treating agent, and also removing some suspending liquid and contaminating by-products with it; these by-products may be in suspension or solution or both. Thus, for example, the suspending liquid may be a hydrocarbon of characteristics, boiling range, etc., similar to the product removed as vapor but having a boiling point curve higher than that of the vapor fraction (temperature as abscissæ, volume as ordinates); such a suspending liquid would be formed from higher boiling constituents of the gasoline being treated. Other suspending liquids of proper physical and chemical characteristics are suitable. Thus, liquids, such as heavy oils, having much higher boiling ranges than the hydrocarbons being treated would be suitable; so also, individual hydrocarbons of proper boiling point may be used.

A great variety of treating agents may be used in our process; some of these are aluminum chloride, sodium, potassium, or alloys such as sodium alloys with other alkali metals or with alkaline earth metals, or with heavier metals as lead, mercury, and the like. We have obtained excellent results with, for example, aluminum chloride, sodium metal (solid and liquid), sodium amalgam and sodium lead alloy.

In this specification we speak of a "suspension" of the treating agent in liquid, but we do not wish to be limited to the physical condition of the medium that this may imply. We do not know whether the success and particular efficacy of our method in producing excellent products is due to the contact with undissolved agent in the liquid or to contact with dissolved agent. It is even possible that some reaction product of the agent and a component of the liquid, or that certain sub-

stances produced by the treating process and included in the term "polymer" or "by-product" as used herein, may either in solution or suspension, or both, contribute to the success of the process. In any event we intend the expressions "treating agent in a liquid" "treating agent in liquid hydrocarbon" or "suspension in a liquid", etc., to cover all these possible physical conditions. By "treating medium" is meant the mixture of liquid and treating agent.

The action of alkali metals on the above mentioned hydrocarbons results in the formation of more or less complex products, some of which may be organic compounds, some compounds of alkali metals, and some sulphur compounds. These products are referred to as "polymer" or "by-product" and are not characterized more definitely because there may be great variation in composition of "polymer" produced from hydrocarbons from different sources or from the same source at different times.

Our preferred application of this general principle comprises passing the hydrocarbons into contact with a medium consisting of alkali metal in liquid hydrocarbon and effecting a more or less continuous removal of the treatment by-products by carrying them out in solution or suspension or both with that part of the treated hydrocarbons which is removed as liquid from the treating vessel.

The treating medium may be atomized or sprayed into contact with the hydrocarbon; the latter may be in the form of vapors, mist, spray or a body of liquid. The treatment can also be effected wholly in the liquid phase. In this case the treating medium and hydrocarbon liquids are mixed, the polymer carried from the reaction vessel by the mixed liquids, and the liquids separated by fractionation with or without filtration to remove the polymer. Usually the treating agent or at least the main portion thereof will remain in the reaction vessel. Therefore, we do not limit ourselves to any particular method of contacting the hydrocarbons with the treating medium because this can be done in many ways without departing from the scope of this invention.

By way of illustration we will describe in detail the particular method of securing the objects of this invention which comprises passing hydrocarbon vapors into a medium consisting of sodium in liquid hydrocarbons, condensing a part of the high boiling constituents to replenish the suspending liquid, removing part of the treated hydrocarbons as vapor and removing some of the liquid from the treating vessel at a rate sufficient to avoid fouling of the vessel by the excessive accumulation in the treating medium of the by-products or other impurities resulting from the treatment.

Figure I illustrates one form of apparatus

suitable for applying the principles of this invention.

Figure II illustrates further adaptations of our invention with special reference to the handling of the suspending liquid.

Hydrocarbon vapors are introduced through the pipe 1, which may carry a condenser 2, through the opening 3, into the treating medium 4, with level at 5, and contained in a vessel or reactor 6. The vessel may be equipped with an agitator 7, driven by the pulley 8 through the shaft 9. The agitator may, under certain conditions, be omitted, the agitation being supplied by the vapors entering the treating medium. The vessel is equipped with a jacket or a coil 10, which is used either for heating or for cooling. Hopper 11 serves for introducing alkali metal into the treating medium through the valve 12 and pipe 13.

A fraction, depending upon the treating temperature, of the hydrocarbon vapors entering the vessel 6 is condensed. This condensed fraction leaves as liquid through a baffle separator 14 and pipe 15, and by a device such as siphon 16, an approximately constant level 5 of the medium is maintained. This liquid is run through pipe 17 and disposed of in various ways.

The portion of the hydrocarbons leaving the reactor as vapor passes through the pipe 18, which may be equipped with a fractional condenser 19 to condense out, if desired, any higher boiling constituents. The liquid thus condensed can be passed into the treating vessel through valve 50 and pipe 51 or it can be removed through valve 52 and pipe 53 and disposed of in any desired way. From the fractional condenser the vapors are led to any suitable recovery system, not shown here.

Exchanger 2 has been referred to as a condenser. Both 2 and the coil 10 can be used either as coolers or as heaters and their purpose is to assist in maintaining the desired treating temperature.

The liquid leaving the reactor by way of separator 14 and pipe 15 consists of the heavier ends, that is, the higher boiling constituents of the gasolines or hydrocarbons treated. This liquid effluent carries with it the polymer formed in the treating vessel.

Inasmuch as the alkali metals are relatively light it is advisable to provide a separator, e. g., a system of baffles as at 14, which will permit effective separation of the alkali metal from the liquid effluent.

The liquid effluent may be handled in a number of ways. For example, with reference to Figure II, it may be sent by way of valve 42 and pipe 43, or, by way of valve 36 and pipe 37, to a proper point for evaporation, cracking, etc. Or, the effluent in pipe 17 can be passed through valve 44 and pipe 45 into a separating device 25 and subjected to centrifuging, filtering, or other method of

separation. Treatment by-products are shown as leaving the separating device at 26, The clarified liquid leaves by way of pipe 27, flowing into a container 28 which acts as a feed reservoir for pump 30, the latter driven by motor 31. The pump receives the liquid through pipe 29 and can deliver it through pipe 32 to any point desired. Thus, the liquid can be caused to flow through valves 33, 38, and 40, and pipe 39, into the treating vessel, thus making it possible with continuous operation and proper temperature control to remove from the treating vessel as treated gasoline practically all of the gasoline line fed except that lost by operation and as polymer. Further, the effluent may be subjected to distillation, and the distillate and polymer residue disposed of as desired. It is to be noted that the effluent has also been subjected to the treating action.

The alkali metal can be fed to the reactor in any convenient manner. It may be prepared as a suspension in liquid hydrocarbon and the suspension added to the reactor by way of hopper 11 or the metal may be added in solid form such as bricks and agitation in the reactor will serve to subdivide it on melting. Other methods may be applied by those skilled in handling such materials. The metal might be added as a liquid or as a finely divided metal in suspension. One method of making and applying colloidal sodium consists in passing a condensed electric spark between two sodium electrodes placed at a suitable distance from each other under a liquid such as ether, xylene, etc.: Such a colloidal suspension is then introduced directly into the treating vessel. It is also possible to make the colloidal suspension directly in the treating vessel itself.

The percentage of the hydrocarbons fed to the treating apparatus which leaves the reactor as liquid is regulated, in general, according to the amount of polymer formed. Enough such liquid must be condensed and removed to carry away the polymer at a satisfactory rate.

In some cases substantially all of the hydrocarbons may be removed as liquid. There would be little point in doing this if gasoline vapors are being treated, but if the gasoline is introduced into the treating vessel as liquid it is entirely feasible to remove substantially all (except perhaps the very lowest boiling constituents which might compose say up to 15 percent of the material) of the gasoline as liquid and distil it for recovery of the finished product. If higher boiling liquid hydrocarbons are being treated, for example, lubricating oil stock, the hydrocarbons can be removed almost entirely as liquid and at the same time a higher temperature of treatment can be maintained, if desired. The effluent liquid may be distilled or treated by such methods as centrifuging, agitating with ab-

sorbent materials, filtration, etc., or combinations of such methods.

In many cases the quality of the hydrocarbons produced by this treatment is satisfactory over a wide treatment temperature range and therefore we prefer to regulate the temperature of operation so that a sufficient quantity of the hydrocarbons is condensed to keep the treating medium in satisfactory operating condition. However, in other cases to secure a satisfactory product it is necessary to use higher treating temperatures even though at higher temperatures the treating medium fouls more quickly per unit of hydrocarbons treated and the polymer has more objectionable physical properties than at lower temperatures.

Operations utilizing higher temperatures may be carried out in at least three ways. Thus at intervals operation may be switched to a spare unit if the first has become excessively fouled. Then, because the alkali metals (except lithium) settle more rapidly than the polymer, a large part of the alkali metal collects in the lower end of the conical bottom of the treating vessel as at 20 and may be drawn off by valve 21 and pipe 22. Or, instead of removing the metal, since the bulk of the polymer which is suspended in the medium settles down just above the alkali metal most of the polymer can be removed, along with a portion of the liquid medium, through the pipe 23 and valve 24, after which the treating vessel is ready for further use. According to the second method the polymer may be removed from the treating medium by effecting a flow, so to speak, in a separate circuit, of higher boiling hydrocarbon. Thus, referring to Figure II, higher boiling liquid in supply tank 35 may be caused to flow through valve 41 and pipe 47 into the treating vessel at a given rate and be removed through pipe 15, with the polymer, the polymer separated from the liquid by settling, filtering, centrifuging or other means as at 25 and the liquid returned by pump 30 through pipe 32 and valves 33 and 34 to the supply tank 35 and then to the treating vessel. It is obvious that the higher boiling liquid need not necessarily be returned to the circuit, but, instead, since it has been treated once it may be utilized, per se, for finished products. In such cases fresh crude higher boiling fractions are introduced into the treating vessel. Some of the higher boiling liquid, depending upon its vapor pressure, leaves the treating vessel with the treated hydrocarbon vapors and, if necessary, may be recovered by subjecting the treated hydrocarbon vapors to a partial condensation process. As a third method it is possible to operate under pressure.

Our invention is not limited to the treatment of hydrocarbon vapors; the apparatus may be utilized for liquid treatment. For

instance, liquid hydrocarbons can be introduced through pipe 1. In this case the coil 10 can be used as a heater. The same treating temperature can be used which would be

employed if the same hydrocarbons were introduced as vapors in which case the greater part of the treated hydrocarbons leave the reactor as vapor through 18. Or, if desired, a lower treating temperature can be used, such that substantially all of the treated hydrocarbons leave the reactor as liquid by way of 14 and 15; the liquid passing, for example, directly to a still from which a final product of good quality is obtained.

15 A great variation in the concentration of alkali metal in the reaction medium is possible. For example, certain cracked gasolines have been successfully refined with as little as 2 grams of sodium per liter of reaction medium. As far as quality of product is concerned there is no upper limit of alkali metal concentration. Other things being equal the rate of treatment will depend on the state of subdivision or surface area of the treating agent.

Example.—This example serves as a specific illustration of this invention. The hydrocarbon mixture treated was crude, cracked gasoline made by cracking certain fractions of Pennsylvania crude petroleum. 87.15 liters of this liquid crude cracked gasoline was passed as vapor into a treating medium consisting initially of approximately 3.5 grams of sodium in 350 cc. of liquid effluent or heavy ends from a previous run, at an average rate of about 1.0 liter per hour. The temperature of the treating medium was maintained at 150°-155° C. (302°-311° F.). At intervals of about 8 hours of running time additional sodium was added to the treating medium. These additions consisted of 2 to 3 grams of the metal in the form of sodium shot. When the run was discontinued the treating medium was in excellent condition and a high quality of product was still being obtained.

69.865 liters of refined gasoline and 15.07 liters of liquid-polymer fraction were recovered. The loss of hydrocarbons was 50 2.215 liters or about 2.54 percent by volume of the feed. The 15.07 liters of liquid effluent amounted to about 17.3 percent of the feed. Approximately 90 percent by volume of this liquid was gasoline of end point equal to that of the crude gasoline before treatment as shown in the distillation data of Table I.

The total weight of sodium introduced into the treating medium for the whole run was 39.5 grams. At the end of the run 12.25 grams of sodium remained in the treating vessel. The sodium consumed, therefore, was 27.25 grams which corresponds to about 0.313 grams per liter or about 0.11 pound per barrel (42 gallons) of crude gasoline fed.

15 Table I shows the distillation data for the

crude cracked gasoline before treatment, the refined gasoline fraction and the liquid effluent after settling out suspended treatment by-products.

Table I

Crude cracked gasoline		Refined gasoline		Liquid effluent	
Percent distilled	Temp. °F.	Percent distilled	Temp. °F.	Percent distilled	Temp. °F.
Start.....	98	Start.....	96	Start.....	90

Table II shows a further comparison of the crude cracked gasoline and the refined gasoline. The percentages of the various hydrocarbons given in the first four items were determined by the method of Egloff and Morrell as given on pages 354-355 of the April, 1926, issue of "Industrial and Engineering Chemistry". The color numbers in the following refer to the Saybolt system, well known to the petroleum industry.

Table II

	Crude gasoline	Refined gasoline
"Unsaturated" hydrocarbons.....	12.33%	10.5%
Aromatic hydrocarbons.....	24.3%	24.9%
Naphthenic hydrocarbons.....	31.1%	32.8%
Paraffin hydrocarbons.....	32.27%	31.8%
Sulphur (lamp method).....	0.0195%	0.007%
Doctor test.....	Positive.	Negative.
Copper strip corrosion test.....	Positive.	Negative.
Odor.....	"Sulphurous"	Sweet.
Color.....	About 18.	Water-white.

The excellent color stability of the refined gasoline fraction is shown by the fact that subjected to sunlight for 7 days the color changed from -30 to 25; other samples placed in a window for 7 days changed in color from -30 to 28; other samples exposed to darkness for 7 days suffered no appreciable change in color.

In order to avoid ambiguity and a multiplicity of claims the following definitions of the terms used in the claims are here given: 120 The term "alkali metal" covers these metals, i. e., sodium, potassium, etc., singly or in various combinations or mixtures with each other or with other metals such as calcium, magnesium, mercury, lead, tin, etc., in any applicable physical state. The term "by-products" covers all of the substances that are formed in the treating medium and that are not removed with the treated hydrocarbon vapors leaving the treating vessel. The 130

term "hydrocarbons" stands for mineral oils, gasolines, and any other hydrocarbon materials that may be improved by such treatment as herein described. By "liquid" is meant any liquid that will not react with the treating agent in such a way as to destroy its effectiveness.

We claim:

1. Process comprising contacting hydrocarbons liquid at the reaction temperature with a treating medium comprising an alkali metal suspended in liquid hydrocarbon, washing contaminating by-products from said alkali metal by agitation with the suspending medium, and removing treated hydrocarbon from the treating medium as liquid effluent, after separating substantially all unreacted alkali metal from said effluent. 10
2. Process comprising passing hydrocarbons liquid at the reaction temperature into a treating medium comprising alkali metal suspended in liquid hydrocarbon, washing contaminating by-products from said alkali metal by agitation with the suspending medium, and removing treated hydrocarbon from the treating medium as liquid effluent. 20
3. Process comprising passing hydrocarbons substantially as vapors into a treating medium comprising sodium suspended in liquid hydrocarbon, washing contaminating by-products from said sodium by agitation with the suspending medium, and removing treated hydrocarbon from the treating medium as liquid effluent. 30
4. Process comprising passing hydrocarbons into a treating medium comprising alkali metal suspended in liquid hydrocarbon having a boiling point curve higher than that of the hydrocarbon introduced, removing treated hydrocarbon from the treating medium as vapor, washing contaminating by-products from said alkali metal by agitation with said higher boiling hydrocarbon flowing through the treating vessel, separating substantially all washed unreacted alkali metal from an effluent portion, and discharging suspended contaminating by-products from the treating vessel suspended in said effluent before fouling quantities accumulate. 40
5. Process comprising passing hydrocarbons substantially as vapors into a treating medium comprising suspended sodium in liquid hydrocarbon having a boiling point curve higher than that of the hydrocarbon introduced and removing treated hydrocarbon from the treating medium as vapor, washing contaminating by-products from said sodium by agitation with said higher boiling hydrocarbon, separating substantially all unreacted sodium from a portion of said hydrocarbon, flowing said portion from the treating vessel at such a rate that suspended contaminating by-products are discharged from the treating vessel before fouling quantities accumulate. 50
6. Process comprising passing hydrocarbons at least partially liquid under the reaction conditions into a treating medium comprising alkali metal suspended in liquid hydrocarbon, washing said alkali metal by agitation with said liquid and removing treated hydrocarbon from the treating medium partially as vapor, and partially as liquid effluent, separating substantially all unreacted alkali metal from said effluent before discharging it from the treating vessel. 70
7. Process comprising passing hydrocarbons substantially as vapors into a treating medium comprising sodium suspended in liquid hydrocarbon, washing said sodium by agitation with said liquid hydrocarbon and removing treated hydrocarbon from the treating medium partially as vapor, and partially as liquid effluent, while separating substantially all unreacted sodium from said effluent before discharging it from the treating vessel. 80
8. Process comprising contacting hydrocarbons at least partially liquid under the reaction conditions with a treating medium comprising alkali metal suspended in liquid hydrocarbon having a boiling point curve higher than that of the hydrocarbon introduced and removing treated hydrocarbon from the treating medium partially as vapor and partially as liquid effluent, separating substantially all unreacted alkali metal from said effluent before discharging it from the treating vessel, and removing treatment by-products from the medium with said liquid effluent. 90
9. Process comprising contacting hydrocarbons at least partially liquid under the reaction conditions with a treating medium comprising sodium suspended in liquid hydrocarbon having a boiling point curve higher than that of the hydrocarbon introduced and removing treated hydrocarbon from the treating medium partially as vapor and partially as liquid effluent, separating substantially all unreacted sodium from said effluent before discharging it from the treating vessel, and removing treatment by-products from the medium with said liquid effluent. 100
10. Process comprising passing hydrocarbons substantially as vapors into a treating medium comprising a treating agent suspended in liquid hydrocarbons having a boiling point curve higher than that of the hydrocarbon introduced; removing treatment by-products from the medium with a liquid effluent continuously flowing from said treating medium at such rate that fouling quantities of said by-products do not accumulate within the treating vessel, while continuously separating substantially all unreacted treating agent from said effluent before discharging from the treating vessel, said treating agent being continuously retained suspended in the said hydrocarbons and within the treating vessel. 110
11. Process comprising passing hydrocarbons substantially as vapors into a treating medium comprising a treating agent suspended in liquid hydrocarbons having a boiling point curve higher than that of the hydrocarbon introduced; removing treatment by-products from the medium with a liquid effluent continuously flowing from said treating medium at such rate that fouling quantities of said by-products do not accumulate within the treating vessel, while continuously separating substantially all unreacted treating agent from said effluent before discharging from the treating vessel, said treating agent being continuously retained suspended in the said hydrocarbons and within the treating vessel. 120
12. Process comprising passing hydrocarbons substantially as vapors into a treating medium comprising a treating agent suspended in liquid hydrocarbons having a boiling point curve higher than that of the hydrocarbon introduced; removing treatment by-products from the medium with a liquid effluent continuously flowing from said treating medium at such rate that fouling quantities of said by-products do not accumulate within the treating vessel, while continuously separating substantially all unreacted treating agent from said effluent before discharging from the treating vessel, said treating agent being continuously retained suspended in the said hydrocarbons and within the treating vessel. 130

11. Process comprising passing hydrocarbons substantially as vapors into a treating medium comprising alkali metal suspended in liquid hydrocarbons having a boiling point curve higher than that of the hydrocarbon introduced; washing treatment by-products from said alkali metal by agitation with said suspending liquid; removing treatment by-products from the medium with a liquid effluent continuously flowing from said treating medium at such rate that fouling quantities of said by-products do not accumulate within the treating vessel, while separating substantially all unreacted alkali metal from said effluent before discharging from the treating vessel.
12. Process comprising passing hydrocarbons substantially as vapors into a treating medium comprising sodium suspended in liquid hydrocarbons having a boiling point curve higher than that of the hydrocarbon introduced; washing treatment by-products from said sodium by agitation with said suspending liquid; removing treatment by-products from the medium with a liquid effluent continuously flowing from said treating medium at such rate that fouling quantities of said by-products do not accumulate within the treating vessel, while separating substantially all unreacted sodium from said effluent before discharging from the treating vessel.
13. Process comprising contacting hydrocarbons at least partially liquid under the reaction conditions with a treating medium comprising alkali metal suspended in liquid hydrocarbon and removing treated hydrocarbon from the treating medium partially as vapor and partially as liquid effluent, separating substantially all unreacted alkali metal from said effluent before discharging it from the treating vessel, and removing treatment by-products from the medium with said liquid effluent.
14. Process comprising passing hydrocarbons substantially as vapors into a treating medium comprising alkali metal suspended in liquid hydrocarbon and removing treated hydrocarbon from the treating medium partially as vapor and partially as liquid effluent, separating substantially all unreacted alkali metal from said effluent before discharging it from the treating vessel, and removing treatment by-products from the medium with said liquid effluent.
15. Process comprising contacting hydrocarbons, at least partially liquid under the reaction conditions, with a treating medium comprising a treating agent suspended in liquid hydrocarbon, removing treated hydrocarbon from the treating medium partially as vapor and partially as liquid effluent, continuously discharging treatment by-products suspended in said effluent from the treating vessel, while simultaneously separating substantially all unreacted treating agent from said effluent before its discharge from the treating vessel and continuously retaining said agent suspended in said liquid hydrocarbon within said vessel, and thereafter separating by-products from the liquid effluent.
16. Process comprising passing hydrocarbons substantially as vapors into a treating medium comprising alkali metal suspended in liquid hydrocarbon and removing the treated hydrocarbon from the treating medium partially as vapor and partially as liquid effluent, separating substantially all unreacted alkali metal from said effluent before discharging it from the treating vessel, removing treatment by-products from the medium with said liquid effluent and separating the by-products from said liquid.
17. Process comprising contacting hydrocarbons at least partially liquid under the reaction conditions with a treating medium comprising a treating agent suspended in liquid hydrocarbon and removing treated hydrocarbon from the treating medium partially as vapor and partially as liquid effluent, separating substantially all unreacted treating agent from said effluent before discharging it from the treating vessel, removing treatment by-products from the medium with said liquid effluent, separating the by-products from said liquid and recycling said liquid through the treating vessel.
18. Process comprising passing hydrocarbons substantially as vapors into a treating medium comprising alkali metal suspended in liquid hydrocarbon and removing treated hydrocarbon from the treating medium partially as vapor and partially as liquid effluent, separating substantially all unreacted alkali metal from said effluent before discharging it from the treating vessel, removing treatment by-products from the medium with said liquid effluent, separating the by-products from said liquid and recycling said liquid through the treating vessel.
19. Process comprising contacting hydrocarbons, at least partially liquid under the reaction conditions, with a treating medium comprising a treating agent suspended in liquid hydrocarbon having a boiling point curve higher than that of the hydrocarbon treated, washing said treating agent by agitation with said suspending hydrocarbon, continuously removing treated hydrocarbon from the treating medium partially as vapor and partially as liquid effluent, continuously discharging treatment by-products suspended in said liquid effluent, while simultaneously separating substantially all unreacted treating agent from the effluent before its discharge from the treating vessel, and continuously retaining said agent suspended in said liquid hydrocarbon within said vessel, and thereafter separating by-products from the liquid effluent.
20. Process comprising contacting hydro-

carbons at least partially liquid under the reaction conditions with a treating medium comprising a treating agent suspended in liquid hydrocarbon having a boiling point curve higher than that of the hydrocarbon introduced and removing treated hydrocarbon from the treating medium partially as vapor and partially as liquid effluent, separating substantially all unreacted treating agent from said effluent before discharging it from the treating vessel, removing treatment by-products from the medium with said liquid effluent, which is flowed out at such a rate that fouling quantities do not accumulate within the treating medium and treating vessel, separating the by-products from said liquid and recycling said liquid through the treating vessel.

21. Process comprising contacting hydrocarbons liquid at the reaction temperature with a treating medium comprising sodium suspended in liquid hydrocarbon, washing contaminating by-products from said sodium by agitation with said liquid hydrocarbon, and removing treated hydrocarbon from the treating medium as liquid effluent, separating substantially all unreacted sodium before discharging said effluent from the treating vessel.

22. Process comprising contacting hydrocarbons at least partially liquid under the reaction conditions with a treating medium comprising sodium suspended in liquid hydrocarbon and removing treated hydrocarbon from the treating medium partially as vapor and partially as liquid effluent; separating substantially all unreacted sodium before discharging said effluent from the treating vessel, and removing treatment by-products from the medium with said liquid effluent.

23. Process comprising contacting hydrocarbons at least partially liquid under the reaction conditions with a treating medium comprising sodium suspended in liquid hydrocarbon and removing treated hydrocarbon from the treating medium partially as vapor and partially as liquid effluent; separating substantially all unreacted sodium before discharging said effluent from the treating vessel, removing treatment by-products from the treating medium with said liquid effluent, separating said by-products from said liquid and recycling said liquid through the treating vessel.

24. Process comprising passing hydrocarbons substantially as vapors into a treating medium comprising a treating agent suspended in liquid hydrocarbons having a boiling point curve higher than that of the hydrocarbon introduced, continuously condensing a sufficient portion of introduced hydrocarbon to suspend and remove treatment by-products with the overflow of said liquid from the treating vessel, and simultaneously

and continuously separating substantially all unreacted treating agent from said overflow before its discharge from the treating vessel and continuously retaining said treating agent suspended in said liquid hydrocarbon within said vessel.

25. Process comprising passing hydrocarbons substantially as vapors into a treating medium comprising alkali metal suspended in liquid hydrocarbon having a boiling point curve higher than that of the hydrocarbon introduced, condensing a sufficient portion of said hydrocarbon vapors in said medium to suspend and remove treatment by-products with overflow of said liquid hydrocarbon from the treating vessel while separating within the treating vessel substantially all unreacted alkali metal from said overflow.

26. Process comprising passing hydrocarbons substantially as vapors into a treating medium comprising sodium suspended in liquid hydrocarbon having a boiling point curve higher than that of the hydrocarbon introduced, condensing a sufficient portion of said hydrocarbon vapors in said medium to suspend and remove treatment by-products with overflow of said liquid hydrocarbon from the treating vessel while separating within the treating vessel substantially all unreacted sodium from said overflow.

27. Process comprising passing hydrocarbons substantially as vapors into a treating medium comprising alkali metal suspended in liquid hydrocarbon under such conditions that a part of the introduced hydrocarbons leaves the treating medium as vapor and a sufficient part is condensed in the medium to wash contaminating by-products from said alkali metal and by its outflow to remove by-products at such rate that fouling quantities do not accumulate within said medium.

28. Process for treating hydrocarbon vapors which comprises subjecting them to fractional condensation in a treating medium, comprising alkali metal suspended in liquid previously produced by such condensation and washing contaminating by-products from said alkali metal and from the treatment vessel by an effluent portion of said condensate.

29. Process for treating hydrocarbon vapors which comprises subjecting them to fractional condensation and treating them in a treating medium comprising alkali metal suspended in liquid previously produced by such condensation and washing contaminating by-products from said alkali metal and from the treatment vessel by an effluent portion of said condensate, separating therefrom substantially all unreacted alkali metal before discharging said effluent.

30. Process for treating hydrocarbon vapors which comprises subjecting them to fractional condensation and treating them in a treating medium comprising alkali metal

suspended in liquid previously produced by such condensation, said medium being maintained at such temperature as to maintain as liquid substantially all the condensate previously produced, and flowing out a portion of said condensate carrying treatment by-products after separating therefrom substantially all unreacted alkali metal.

31. Process for treating hydrocarbon vapors which comprises fractionally condensing a portion of said hydrocarbons and passing the vapors remaining into a medium formed by suspending alkali metal in a hydrocarbon liquid obtained by such fractionation, removing contaminating by-products from said alkali metal by agitation with said liquid and discharging by-products suspended in a portion thereof after separating substantially all unreacted alkali metal therefrom.

32: Process for treating hydrocarbon vapors which comprises passing them in contact with alkali metal suspended in liquid hydrocarbon maintained at such a temperature that a sufficient fraction of said vapors is condensed in said liquid hydrocarbon, to discharge contaminating by-products suspended therein at such a rate that fouling amounts do not accumulate within said contacting liquid.

33. In a process for treating hydrocarbon vapors with alkali metal, the step which comprises removing solid treatment by-products from said alkali metal by means of liquid hydrocarbon, while separating and retaining unreacted metal within the treating vessel and discharging said by-products suspended in an effluent portion of said liquid.

34. In a process for treating hydrocarbon vapors with alkali metal, the step which comprises removing solid treatment by-products from said alkali metal by means of liquid hydrocarbon obtained by condensing a portion of said hydrocarbon vapors, while separating and retaining unreacted metal within the treating vessel and discharging said by-products suspended in an effluent portion of said liquid.

35. In a process for treating hydrocarbon vapors with a medium consisting of alkali metal suspended in liquid hydrocarbon, the step which comprises fractionally condensing a sufficient portion of said vapors to furnish liquid hydrocarbon to suspend and separate contaminating by-products from said alkali metal and remove said by-products at such a rate that fouling quantities do not accumulate within the treating vessel.

36. Process consisting in maintaining a liquid substantially inert to sodium containing finely divided sodium at a predetermined temperature, passing hydrocarbons having a boiling point curve below said temperature into said liquid and flowing out a portion of said liquid carrying treatment by-products

from the treating zone after separating substantially all unreacted sodium from this effluent and recovering treated hydrocarbons.

Signed at Niagara Falls, in the county of Niagara and State of New York, this 19th day of November, A. D. 1927.

PAUL JOHNSON CARLISLE.
CHARLES ROBERTS HARRIS.
